UNITED STATES PATENT OFFICE.

EDMUND SCOTT GUSTAVE REES, OF STAFFORD, ENGLAND.

CENTRIFUGAL PUMP, TURBINE, CONDENSER, AND THE LIKE.

1,166,257.

Specification of Letters Patent. Patented Dec. 28, 1915.

Application filed November 1, 1913. Serial No. 798,759.

To all whom it may concern:

Be it known that I, EDMUND SCOTT GUSTAVE REES, a subject of the King of Great Britain, residing in Stafford, England, have 5 invented certain new and useful Improvements in Centrifugal Pumps. Turbines, Condensers, and the like, of which the following is a specification.

This invention relates to centrifugal 10 pumps, turbines, condensers and the like apparatus of the type wherein the impeller is constructed to form a pressure fluid chamber or reservoir of large capacity and is provided at its periphery with nozzles of small 15 area and short length which are adapted to convert part of the pressure energy into speed energy and thereby to control the direction of discharge of the fluid relative to the external casing.

20 The present invention relates mainly to the construction of the impeller in apparatus of this class, and its primary object is to reduce the weight and size and cost of construction without impairing the efficiency 25 of the apparatus.

The improved construction is designed to 30 secure maximum capacity of the pressure reservoir at its most effective part, namely close to the periphery of the impeller, and according to the present invention two expedients are adopted whereby this advantage is insured.

35 The discharge nozzles are arranged in a peripheral trough having parallel or mutually inclined side walls and occupying the central portion of the peripheral space of the impeller, leaving upon either side of this nozzle trough an inverted trough forming part of the pressure reservoir, thereby securing to the latter the space which is most valuable for the development of pressure 40 by centrifugal force. The nozzles may therefore be regarded as dipping inwardly from the periphery of the reservoir into its interior, instead of projecting outwardly from the periphery of the reservoir.

In one construction according to the present invention the side walls of the nozzle trough are saw-tooth shaped around their 50 inner edges, while the floor of the trough is discontinuous circumferentially and consists of a series of inclined plates, usually slightly curved, which connect the inner edges of the side plates leaving the short radial sides 55 inclosed to form the apertures of the discharge nozzles. The fluid pressure space at

the two sides of this trough may be formed by the fixed casing, in which case the impeller becomes an open broad bladed paddle wheel with more or less radial blades, sur- 60 mounted by the nozzle trough, or the rim of the impeller may be shrouded so as to form a hood or peripheral pressure trough inter- 65 laced with the nozzle trough, the depth of this hood (which forms the most effective 70 part of the pressure reservoir) being preferably about the same as the depth of the discharge nozzles so that the sides of the impeller are left open for inspection or cleaning. Instead of having an open or a hooded 75 impeller it may be shrouded and the side walls may extend to the eye, but the sides of the impeller or paddle are preferably inclined inwardly toward the eye, so that the width of the pressure chamber increases 80 from the inlet toward the periphery, and the running eye joint between the impeller and the fixed casing is preferably on the outside of the fixed bush or joint flange of the casing, because with the pressure chamber type 85 of impeller the difference of pressure causing leakage from the periphery to the eye joint is reduced as the eye joint becomes larger in diameter until a point is reached when the periphery and eye joint pressures 90 balance, at which point the running eye joint becomes superfluous. This is therefore the correct diameter for the inside of the hood or peripheral pressure trough. A greater diameter than this tends to reverse 95 the direction of leakage in the case of water pumps working against a head. In the case of the open or the hooded impeller the walls of the fixed casing forming the sides of the pressure chamber entirely or partly should 100 be inwardly inclined toward the opening through which the fluid enters the impeller, and should fit the sides of the impeller. Further, the sides of the nozzle trough may be continued outwardly to form a radial 105 extension of the trough with either parallel or mutually inclined walls, this annular space constituting a free vortex channel rotating with the impeller, wherein the streams of water from the nozzles distribute themselves and acquire a uniform swirl before entering the outwaters or expanding channel or channels in the fixed casing, when such are provided. By this arrangement of discharge trough with nozzles formed independent of the pump blades, the water can 110 be discharged from the most effective part

of the pressure chamber according to the conditions for which the pump is designed. For instance, if the impeller is designed with rearwardly directed nozzles for self regulation when dealing with varying lifts, the discharge openings of the nozzles would naturally be on the pressure or driving side of the pump or paddle blades, the nozzles having if desirable flared openings to give good entry. Similarly, if it is intended to direct the nozzles so as to discharge in a forward direction and thus obtain increased resultant discharge velocity, or the same velocity of discharge at a lower speed, but without self-regulation, the discharge nozzles are disposed so that their openings are just in advance of the paddle blades.

The invention is illustrated in the accompanying drawings, wherein:—

20 Figure 1 is a central longitudinal section of a completely closed or shrouded impeller with part of the external casing, constructed according to the present invention; Fig. 2 is a transverse section of the same partly on line A—B and partly on line C—D of Fig. 1; Figs. 3 and 4 are views corresponding to Figs. 1 and 2 of a semi-inclosed or hooded impeller, Fig. 4 being a section partly on line E—F and partly on line G—H of Fig. 3; Figs. 5 and 6 are corresponding views showing a modified construction, wherein the rim portion and the vane portion of the impeller are constructed separately; Fig. 6^a is a view corresponding with Fig. 5 but showing the discharge nozzles forwardly directed; Fig. 7 is a part end elevation of an impeller casting, the separately formed end walls being removed to show the pressure reservoir cavities; and Fig. 8 is a section on line 8—8 of Fig. 7.

Referring first to the construction of Figs. 1 and 2, the impeller consists of a boss *a* carrying blades or vanes *b* which extend from the eye *c* to the periphery *d* of the impeller the sides *e* of which slope inwardly from the rim toward the eye. The peripheral discharge outlets *f* are formed within a trough or channel extending around the periphery of the impeller, the side walls *g* of this trough, which may be mutually inclined or may be parallel as shown, forming the sides of the nozzle, while the outer and inner walls of the nozzles are formed by successive portions of the floor *h* of the trough which, as shown, is stepped so that the trough consists of a series of triangular portions each of a depth varying from zero or approximately zero at the lip of the discharge nozzle to a maximum at or near the point of greatest constriction of the nozzle. There are thus left on each side of the nozzle trough annular chambers *i* of the full diameter of the impeller, wherein a mass of liquid at high pressure due to centrifugal force is stored. The inlets *c* of the impeller

are formed of the requisite diameter for the maximum output fixed by practice for a given impeller, and the fixed bush or joint ring *k* of the casing is formed with a coned flange the inner surface of which forms a 70 continuation of the side wall of the impeller. This construction enables the effective aperture of the impeller eye to be varied simply by turning down the edge of the coned flange to a greater or less extent. 75

The side walls *g* of the nozzle trough may be continued outwardly as indicated at *g*^o to form an annular vortex chamber rotating with the impeller, and the walls of this vortex chamber may be outwardly inclined 80 or curved as shown or may be parallel with each other like the walls of the nozzle trough, or inwardly inclined.

In the construction of Figs. 3 and 4, to which are applied the same reference characters used to denote the corresponding parts in Figs. 1 and 2, the side walls *e* of the impeller extend inwardly only to a distance slightly greater than the depth of the nozzle trough, the continuation of the 90 side walls of the pressure reservoir being constituted by the coned plates *k* of the fixed casing, which to facilitate construction or for renewal may be made separate from the rest of the casing and fixed thereto in a 95 manner similar to that whereby the ring *k* is shown secured in Fig. 1.

It will be seen that the area of the eye of the impeller is determined by the aperture at the apex of the coned wall or plate *k* 100 and that therefore no modification of the impeller itself is required in order to adapt the apparatus for an increased flow of water through the eye, this being readily effected by boring out the inner edge of the 105 plates *k* to the requisite extent. Further it will be seen that with the mutually inclined walls *k* (which in practice would probably form an angle of from 30° to 60° with each other) there is less liability of the rubbing 110 surfaces between the impeller and the casing becoming fouled or cut up by grit or other solid matter in the liquid which is dealt with, since such solid matter is thrown outward radially by centrifugal force and 115 therefore is not projected along or against such rubbing surfaces.

In the construction of Figs. 5 and 6 the peripheral part of the impeller including the nozzle trough and the hood constituted 120 by the periphery *d* and side walls *e* are formed separately from the paddle wheel center consisting of the boss *a* and vanes *b* which latter are formed integral with the boss and may have their outer edges accommodated in grooves in the hood *d*, *e* or 125 the two portions may be made a driving fit and secured by any suitable means.

In the modified construction shown in Figs. 7 and 8 the boss *a* of the impeller, 130

blades *b*, shrouded periphery *d*, *e*, side walls *g* and floor *h* of the nozzle trough are cast integrally with each other, the two side walls of the impeller wheel in which the inlets or eyes to the interior of the impeller are formed being separately constructed. The views given of this construction are designed to emphasize the disposition of the nozzles with respect to the periphery of the pressure chamber, and it will be seen that the lower edge (represented in Fig. 8, by the line *h*) of the inlet aperture of the nozzles extends very considerably into the interior of the impeller, while apart from the slightly projecting extension walls *g*, the delivery edge of the floor or inner wall *h* of the nozzle is of the same diameter as the full diameter of the annular troughs *i* in the pressure fluid reservoir.

20 It will be understood that many constructional modifications may be made in the apparatus herein described.

Having thus described the nature of the said invention and the best means I know 25 of carrying the same into practical effect, I claim:—

1. In a centrifugal pump or the like, an impeller comprising a peripheral rim having a trough projecting inwardly therefrom 30 and occupying the central portion thereof and having discharge nozzles formed in said trough.

2. In a centrifugal pump or the like, an impeller comprising a peripheral rim having a trough projecting inwardly therefrom 35 and occupying the central portion thereof and having discharge nozzles formed in said trough, said trough having its side walls continued outwardly from the rim to form a radial extension of the trough.

3. In a centrifugal pump or the like, a 40 rotatable impeller having inlet apertures, a fixed casing within which said impeller rotates and having parts which surround the inlet apertures of the impeller, said impeller comprising a peripheral rim having a nozzle trough projecting inwardly from and occupying the central portion of the same, said rim further having lateral portions projecting inwardly to meet the parts of the casing which surround the inlet apertures of 45 the impeller and forming with the latter and with the two sides of said trough a

pair of inverted annular troughs which constitute parts of the pressure reservoir of the 55 impeller.

4. In a centrifugal pump or the like having an impeller containing a pressure fluid chamber of relatively large capacity and rotatable within a fixed casing, a nozzle trough 60 projecting inwardly from and occupying the central portion of the peripheral rim of the impeller, said rim having lateral portions which project inwardly to meet parts of the fixed casing surrounding the inlet apertures 65 of the impeller and form with the two sides of the trough and the said parts on the casing, a pair of inverted annular troughs constituting parts of the pressure reservoir of the impeller, said lateral rim portions and 70 fixed parts carried by the casing being respectively mutually inclined to each other so that the width of the pressure reservoir increases outwardly toward the rim of the impeller. 75

5. In a centrifugal pump or the like having an impeller containing a pressure fluid chamber of relatively large capacity and rotatable within a fixed casing, comprising detachable parts or joint rings surrounding 80 the inlet apertures of the impeller, a nozzle trough projecting inwardly from the peripheral rim of the impeller, said rim having lateral portions projecting inwardly to meet the outer faces of the said joint rings and 85 forming with the sides of the trough and the joint ring a pair of inverted annular troughs constituting parts of the pressure reservoir of the impeller, substantially as described. 90

6. A centrifugal pump or the like having an impeller fitted with a number of vanes and having extending around its periphery an inwardly projecting trough with peripheral discharge nozzles formed therein, 95 the inlet openings of the discharge nozzles being disposed somewhat in advance of the vanes, substantially as described.

In testimony whereof I have signed my name to this specification in the presence of 100 two subscribing witnesses.

EDMUND SCOTT GUSTAVE REES.
